UNITED STATES PATENT OFFICE.

GEORGE W. STAFFORD, OF PROVIDENCE, RHODE ISLAND, ASSIGNOR TO
THE KNOWLES LOOM WORKS, OF WORCESTER, MASSACHUSETTS.

LOOM.

SPECIFICATION forming part of Letters Patent No. 562,344, dated June 16, 1896.

Application filed October 11, 1893. Serial No. 487,831. (No model.)

To all whom it may concern:

Be it known that I, GEORGE W. STAFFORD, a citizen of the United States, residing at Providence, in the county of Providence and State of Rhode Island, have invented certain new and useful Improvements in Looms, of which the following is a specification, reference being had therein to the accompanying drawings.

10 The invention has reference particularly to
looms containing shifting or change shuttle-
boxes and fancy shedding mechanism. In a
loom having these features there are em-
ployed, usually, one set of pattern devices
15 pertaining to the box-motion and determining
the movements of the shuttle-boxes, and an-
other set of pattern devices pertaining to the
shedding mechanism and determining the
movements of the harness-frames. Each of
20 such sets of pattern devices has its pattern
barrel or cylinder, to which latter is commu-
nicated an intermittent or step-by-step move-
ment of rotation, as is well known, the ad-
vance of the pattern-cylinder of the box-mo-
25 tion occurring a little after that of the pat-
tern-cylinder for the shedding mechanism.
It usually is the case that each of the said
pattern-cylinders has a set of actuating de-
vices which is separate from that for the other
30 thereof, this being necessitated by the fact
above indicated that the timing of the move-
ments of the pattern-cylinders is such that
the latter are not advanced simultaneously
but successively. Usually, also, the said actu-
35 ating devices are not positive in their engage-
ment with the pattern-cylinders, but move
the same through pawls and ratchets. This
arrangement is objectionable in various re-
spects, among which is the frequency with
40 which the pattern-chains passing around the
two pattern-cylinders become disarranged
relatively to each other, after the pattern-
cylinders have been turned in either direc-
tion by hand. For example, ordinarily in
45 working the loom by hand, as when finding
a mis-pick, the pattern-cylinders have to be
separately turned backward by hand, and
this is likely to result in the disarrangement
aforesaid.

50 My invention has for its object to provide
in simplified and improved manner for com-

municating to the two pattern-cylinders aforesaid the necessary movements at the proper times in the working of a loom, and with the required difference of time in order of actuation, and whereby disarrangement of the two pattern-chains relatively to each other shall be practically rendered impossible. 55

It consists in a novel combination and arrangement of devices wherein the said pattern-cylinders are both actuated in either direction in a positive manner by a single shaft, which is driven from one of the shafts of the loom, all as will now first be described fully with reference to the accompanying drawings, and afterward particularly pointed out and distinctly defined in the claims at the close of this specification. 65

In the drawings, Figure 1 is a view in front elevation of part of a loom having my invention applied thereto, enough of the loom being shown to render clear the connection and relations of the devices embodying the invention. Fig. 2 is a view of the same in side elevation viewed from the left-hand side in Fig. 1, certain parts which are visible in Fig. 1 being omitted from Fig. 2, because unnecessary to be shown in the latter. Figs. 3, 4, and 5 are detail views of parts which are involved in the invention.

At 1 in the drawings is shown part of the framing of a loom. At 2 is shown the framing of the shedding mechanism, it pertaining to a shedding mechanism of that kind which is known as a "dobby." At 3 is shown the 85 crank-shaft of the loom, at 4 the pattern barrel or cylinder of the shedding mechanism, and at 5 the pattern-barrel or pattern-cylinder of the box-motion. All of these parts are or may be as common in the construction of 90 looms.

For the purpose of rotating intermittently both pattern-cylinders, I provide an upwardly-extending shaft 6, the same occupying usually the inclined position which is represented in Fig. 1, it actuating the respective pattern-cylinders through pin-wheels and star-wheels, and being geared to one of the shafts of the loom, by which shaft it is driven. Thus at 7 is a bevel-gear that is secured on the crank-shaft 3 of the loom, and at 8 is a second bevel-gear that is secured on the lower

end of the inclined shaft 6, it being in engagement with the bevel-gear 7, and the shaft 6 thereby being driven from the shaft 3.

At 9 and 10 are pin-wheels which are fixed 5 on the upper portion of the inclined shaft 6, the said pin-wheels, respectively, being arranged to engage the crown-shaped star-wheels 11 and 12, which latter, respectively, are fixed on the shafts 13 and 14, respectively, 10 of the pattern-cylinders 4 and 5. Thereby, as the crank-shaft rotates, the upwardly-extending inclined shaft 6 is rotated also, and the pattern-cylinders are intermittently advanced upon their individual axes. Inasmuch as the pattern-cylinder 5 of the box-motion should receive movement somewhat after movement is communicated to the pattern-cylinder 4 of the shedding mechanism, the pin-wheel 10 is set on shaft 6, so as to 15 reach and engage the star-wheel 12 after pin-wheel 9 reaches and engages star-wheel 11. This arrangement is clearly shown in the drawings. The pin-wheels and crown-shaped star-wheels which are shown in the drawings, 20 and which I prefer to employ, differ from the pin-wheels and star-wheels that usually are employed in that they are not constructed to interlock in a manner to prevent rotation of the star-wheels while the pins of the pin-wheels are absent from the slots of the star-wheels. 25 Usually, the said wheels are constructed thus to interlock. Therefore, for the purpose of preventing the pattern-cylinders from overrunning after having been turned 30 by the action of the pins of the pin-wheels in slots of the star-wheels, and also in order to hold each pattern-cylinder in the right position while stationary, I provide checking devices which are arranged to coact with the 35 respective pattern-cylinders. These checking devices consist of a disk or wheel 141, fixed 40 on the shaft of each pattern-cylinder and having a notched periphery, a coöperating arm or lever 15, which is pivoted to a convenient 45 portion of the fixed framework, as shown, and which has a portion thereof shaped to enter and fit the notches of the said disk or wheel, and a spring 16, having one end thereof connected to a fixed point on the framing and 50 the other to the arm or lever 15, the said spring operating to press the arm or lever against the periphery of the disk or wheel.

The checking devices for the pattern-cylinder of the shedding mechanism are shown 55 best in Fig. 1 of the drawings. Those for the pattern-cylinder of the box-motion are shown separately in Fig. 5. Preferably, the portion 61 of the inclined shaft 6 on which the pin-wheels 9 and 10 are fixed is separated 60 from the lower portion 62 thereof, on which the bevel-gear 8 is fixed, (see Figs. 3 and 4,) the two portions 61 and 62 of the said shaft 6 being coupled together normally by means 65 of a clutch 17, the lower member of which is fixed to the lower portion 62 of the shaft, while the upper member thereof is arranged

to be slid up and down on the upper portion 61 of said shaft by means of a rock-shaft such as that shown at 18 in the drawings. On the upper portion 61 of the shaft 6 is 70 fixed a hand-wheel 19, by means of which to rotate the said upper portion 61, after it has been uncoupled or unclutched from the lower portion 62, and when it is desired to move the two pattern-cylinders either backwardly 75 or forwardly in unison without at the same time operating other parts of the loom.

The foregoing devices for operating the two pattern-cylinders are simple and convenient. They operate both thereof positively 80 in proper harmony and unison, and also with the desired relative timing in the movements communicated thereto. Should the loom be worked backwardly by hand more than one pick, as frequently is the case, the said devices rotate the two pattern-cylinders 85 reversely to a corresponding extent in a positive manner, thus carrying backwardly the pattern-chains which pass around the pattern-cylinders. In the case of devices containing pawls for turning the pattern-cylinders, the latter must be turned backwardly 90 by hand when the loom is reversed. In consequence of having both of the pin-wheels fixed on a single shaft, the two pattern-cylinders 95 cannot become relatively disarranged while the loom is being reversed, or while the said pattern-cylinders are being moved or adjusted in either direction by hand. A particular advantage of my devices is the 100 fact that when the pins of the pin-wheels are out of the slots in the corresponding star-wheels, which is the case when the lathe of the loom is in its back position, each pattern-cylinder is free to be turned independently 105 by hand in either direction to any extent desired. The checking devices not only prevent overrunning, but they operate at all 110 times to insure proper positions of the pattern-cylinders after the completion of movements thereof in either direction, and thus protect against the breakage which would result if a slot of either star-wheel were not presented in position to be entered by the pin of the corresponding pin-wheel when the 115 latter is rotated in the regular running of the loom. The said checking devices thus 120 perform an important function in connection with the pin-wheels and star-wheels described, for, as hereinbefore set forth, the latter are without the locking arrangements 125 with which similar wheels generally are provided, and were it not for the checking devices the pattern-cylinders and connected star-wheels might accidentally assume positions which would prevent the pins from entering the slots.

I claim as my invention—

The combination with the pattern-cylinder of the shedding mechanism, a star-wheel connected therewith, the pattern-cylinder of the box-motion, and a star-wheel connected there-

with, of an upwardly-extending shaft composed of sections provided with devices for coupling them together and uncoupling them when required, a hand-wheel and pin-wheels affixed to the upper section of the said shaft, the said pin-wheels engaging with the said star-wheels, a shaft of the loom, and gearing intermediate the same and the lower section

of the said upwardly-extending shaft, substantially as described.

In testimony whereof I affix my signature in presence of two witnesses.

GEORGE W. STAFFORD.
